RAILWAY SIGNALING SYSTEM

John S. Miller, Chicago, Ill., assignor to Associated Electric Laboratories, Inc., Chicago, Ill., a corporation of Delaware

Application October 30, 1933, Serial No. 695,836

15 Claims. (Cl. 246—122)

This invention relates to signaling systems for railroads, and more particularly to train reporting equipment for use in connection with telephone train dispatching systems, so arranged that the train dispatcher may receive at all times an indication or signal reporting the passage of a train at certain points along a railroad, usually an isolated place where there is no train operator on duty. The dispatcher is thereby enabled to better determine the location of trains under his supervision and dispatch them to better advantage.

The principal object of the invention is to devise an arrangement of parts and apparatus in a train reporting system by means of which a train dispatcher is informed at all times of the passage of trains along certain sections of the railroad track.

A further object is to arrange the system so that the location of the particular point or way station through which a train is passing is automatically transmitted to the dispatcher.

A further object resides in the means whereby the direction in which a train is proceeding through a given point or way-station is automatically transmitted to the dispatcher.

An additional object is to provide means whereby the train reporting system operates to signal the dispatcher over the regular train dispatcher's line connecting all the way-stations, without interfering in any way with the normal operations over the line such as the selecting functions and telephone communications.

Another object of the invention is concerned with the means whereby the dispatcher is not required to set the apparatus at any of the points along the railroad so it will operate upon the passage of a train, the equipment operating automatically and continuously as long as trains are passing the given points, and it only comes to rest in normal position after having been operated due to the passage of a train by the act of the dispatcher operating a selector over the line at the point or station.

The invention contemplates an arrangement whereby at certain isolated points or way-stations along a railroad whereat no attendant is on duty, the railroad track is divided into a number of insulated sections, and at each of these way-stations equipment is provided comprising a group of relays together with a rotary selective switch. In addition the usual way-station type of selector controlled by a dispatcher is provided. The equipment at each way-station is connected to the dispatcher's signal line so that the appa-

ratus which is operated responsive to the passage of the train at the point, automatically transmits indications over the dispatcher's line to the dispatcher's position notifying him of the particular point at which the train is passing and its direction of movement.

The various objects and advantages of the invention will more fully appear hereinafter in the detailed description, reference being had to the accompanying sheet of drawing which diagrammatically depicts a preferred embodiment of the invention.

In the drawing a section of railroad track is disclosed which is divided into three sections, each insulated from the other. The section "J" represents a section located in a northern direction from the intermediate section "K" representing the given point or way-station. The section "L" represents a south position of the track. Track relay "TN" is connected to opposite rails of the track section "J" to which the battery 60 and the resistance 61, is also connected to normally maintain relay "TN" in an energized condition. Track relay "TS" is similarly connected to the south track section "L" and is maintained energized by means of battery 62 thru resistance 63 connected with section "L".

The track relays "TN" and "TS" may be the usual railroad type of track relay commonly provided for operating semaphore signals and like apparatus. These relays in addition to contacts for controlling the foregoing are provided with contact 5 on relay "TN" and contact 6 on "TS". The track relays "TN" and "TS" as is well known may likewise be arranged to be connected to the track sections in such a manner that they will become energized consequent to the passage of a train instead of being normally energized as shown.

In describing the operation of the system it will be assumed that a railroad train indicated at 85 is proceeding in a northerly direction over the railroad track, past the given point or way-station "K". In doing so it first enters the track section "L" and thru the medium of the car wheels and axle it places a shunt circuit across the rails, thereby short circuiting relay "TS" from battery 62, the resistance 63 preventing a direct short on the battery. As a result the track relay "TS" deenergizes and drops back its armature 6 to extend ground from its back contact over conductor 61 thru the winding of the control relay "CS" to battery. Relay "CS" thereupon energizes and at its armature 8 closes its front contact to ground which is extended through arma-

ture 9 and its back contact and through the winding of directional relay "DS" to battery. Relay "DS" upon energizing disconnects its back contact from armature 12 to prevent the energization of directional relay "DN" at this time. At its front contact and armature 13 relay "DS" prepares a locking circuit for itself. At its front contact and armature 14 it prepares a circuit for wiper 40 of the code switch to the coder relay "CO". A branch of the grounded circuit extending from armature 8 of control relay "CS" extends thru the winding of relay "SS" to battery. At its armatures 20 to 24 inclusive upon energizing it prepares circuits extending thru the front contacts.

It is assumed now that the train has passed thru the track section "L" and entered the section "K". The section "K" is insulated from the track section "L" and is a short length of track compared to sections "J" and "L"; it being assumed that a full train of cars can be accommodated by track sections "J" and "L" and only one car or less by section "K". With this assumption the train entering the section "K" will still have a number of cars passing thru section "L" so that track relay "TS" will not again become energized due to the exit of the train from section "L".

The train now proceeding north enters into the section "J" and it will be seen, overlaps sections "J", "K" and "L". Relay "TN" immediately deenergizes because it is short-circuited by the train wheels across the rails of section "J". Relay "TN" upon falling away closes ground from its back contact and armature 5 over conductor 62 and thru the winding of relay "CN" to battery. Relay "CN" thereupon energizes and extends ground from its armature 7 thru the winding of relay "SN" to battery. A branch of this circuit extends to armature 12 of the directional relay "DS" but as this relay is now in an operated position relay "DN" cannot energize. As a result of the energization of start relay "SN" it closes its armatures 15 to 19 inclusive on to its front contacts. With relays "SN" and "SS" energized, a locking circuit for relay "DS" is now closed extending from ground on back contact of armature 25 of stop relay "ST", front contact and armature 20, armature 15 and its front contact, locking armature 13 and its front contact thru the winding of directional relay "DS" to battery. Relay "DS" therefore remains energized as long as the stop relay "ST" is at normal. A branch of the grounded circuit from armature 25 of the stop relay "ST" likewise extends thru armatures 21, 16, 22 and 17 and their front contacts in parallel to the windings of relays "SN" and "SS" so that these relays likewise remain locked up under the control of stop relay "ST". The train may now pass completely outward from the track section "J", track relay "TS" and shortly afterwards track relay "TN" assume their normal condition by again being maintained energized from the track batteries 60 and 63 respectively. At their armatures 5 and 6 these relays open the circuit of control relays "CN" and "CS", which in turn upon deenergizing restore their respective armatures 7 and 8. Directional relay "DS" and start relays "SN" and "SS" are now locked in an energized condition thru their own contacts independent of control relays "CN" and "CS".

As a further result of the energization of start relays "SN" and "SS" a circuit is completed extending from ground on front contact and armature 18, armature 23 and its front contact, armature 26 and its back contact, interrupter springs

29 thru the winding of the stepping magnet "M" to battery. This stepping magnet "M" energizes and at its interrupter contacts 29 interrupts its own circuit to deenergize.

The code switch comprises a number of wipers 40 to 43 inclusive, which are adapted to be rotated in a forward direction across their associated bank contacts under control of the stepping magnet "M" by means of any known stepping device such as a pawl and ratchet arrangement. Each of the wipers are arranged at their ends so that in their rotation over their respective bank contacts they will always be in engagement with two of them as they pass from contact to contact; in other words they will engage a succeeding contact 15 before passing from the preceding one. This type of rotary stepping switch is well known and it is not deemed necessary to further describe its construction.

As has been stated, the stepping magnet "M" is energized from the grounded armature 18 and it immediately opens its own circuit at contacts 29 so that upon falling away it rotates or steps the wipers 40 to 43 inclusive in a forward direction on to the first set of bank contacts. The stepping magnet "M" operates in the aforesaid manner continuously to rapidly rotate the wipers. It will be observed that wipers 40 and 41 are normally resting on the last set of bank contacts while wipers 42 and 43 are normally resting on their first set. Immediately upon wiper 42 engaging the first one of the two bank contacts 76, a circuit is closed extending from battery on contact 76, wiper 42, wire 64, resistance R1, (for reducing the current flow) winding of the coder relay "CO", back contact and armature 26, front contact and armature 23, to ground by way of contact and armature 18. The coder relay "CO" immediately energizes over this circuit to close its front contact on armature 23. This results in a circuit being completed from the aforesaid ground on armature 18, thru armatures and contacts 23 and 26, front contact and armature 28, conductor 53 thru the primary winding 47 of the induction coil "IC" to battery. The current flowing thru this 45 circuit induces a current flow in the secondary winding 48 of the induction coil "IC". This induced current is in turn transmitted over a circuit extending thru back contact and armature 27, adjustable resistance "R", condenser "C", front contacts and armatures 24 and 19 in parallel, and outward over line conductors 54 and 55, which are connected to the dispatcher's line comprising conductors 50 and 51 terminating in the dispatcher's position, and thru the equipment thereat including the transmitter and receiver "RC". The induced current flowing over the aforesaid circuit produces an audible "click" or sound in the receiver "RC" which is assumed to be always in position for listening on the head of the dispatcher. In the above traced circuit the adjustable resistance "R" may be regulated to modify or increase the amount or loudness of the "click" from the induced current, while the condenser "C" in this circuit prevents shunting, of the dispatcher's line conductors 50 and 51 so as not to interfere with other functions, such as selecting or telephone conversations which may be taking place over the line.

The wiper 42 under the further action of stepping magnet "M" now engages the second one of bank contacts 76 before it leaves the first one. The interval between the stepping of wiper 42 from the first of contacts 76 to the second constitutes an interval of time which is arbitrarily as- 75

sumed to correspond to a "dot" in the Morse type of code signaling. Immediately that wiper 42 disengages from the second of contacts 76 and thereupon engages a dead contact, the circuit of the coder relay "CO" is interrupted and it thereupon restores its armature 28. The cessation of current flow in the primary winding 47 of the induction coil "IC" induces another current flow in the secondary winding 48, which is in turn propagated over conductors 54 and 55 to the dispatcher's line conductors 50 and 51 to produce a second audible "click" in the receiver "RC" at the dispatcher's position. The dispatcher being versed in the Morse code of signaling will understand that the short interval of time between the "clicks" after wiper 42 engages the first and then disengages the last of the bank contacts 76 corresponds to a "dot" in the Morse code of signaling. The wipers continue to advance under control of stepping wiper "M" and wiper 42 engages the fourth bank contact 77 after an interval which is longer than the interval between the two bank contacts 76 representing the "dot". This interval indicates the separation between two characters of a letter to the dispatcher. The engagement of wiper 42 with the first of bank contacts 77 produces another "click" in the dispatcher's receiver "RC" from the induction coil over the previously traced circuit; relay "CO" being again energized as a direct result. As wiper 42 steps forward over the four bank contacts 77, relay "CO" is maintained energized and when the wiper leaves the last of the set of contacts it restores and upon opening its contacts 28 produces another "click" in the dispatcher's line from the induction coil "IC". The interval between the wiper 42 engaging the first of contacts 77 and leaving the last one comprises an interval which is interpreted by the dispatcher as representing a "dash" in the code. The wiper 42 has therefore transmitted a "dot" and "dash" to the dispatcher which in the Morse code is representative of the letter "A", this letter conveying to the dispatcher part of a symbol or code representing the point or way-station "K" thru which the train has passed.

The wipers all continue to rotate under control of stepping magnet "M" and after wiper 42 steps off of the last one of bank contacts 77 it is no longer effective. Shortly after the wipers rotate a number of steps over dead contacts, so that an interval of time elapses during which no signals are being sent, wiper 43 then engages the first one of a group of bank contacts 78 and under the control of the stepping magnet "M" makes contact in succession with each of the four bank contacts 78. When the wiper reaches the first bank contact 78 the coder relay "CO" energizes and remains so until it falls back due to wiper 43 stepping off the last of the bank contacts 78. At armature 28 the coder relay "CO" energizes the primary winding 47 of the induction coil "IC" and thereby induces a current flow in the secondary winding 48 which produces a "click" in the dispatcher's line circuit which is audible in receiver "RC". When wiper 43 steps off of the last bank contact 78 the "click" is again reproduced due to the deenergization of the coder relay "CO". The interval between the first and the second "clicks" in the receiver "RC" represents a "dash" in the Morse code. Wiper 43 then steps to a dead contact in its bank after which it engages successively the two bank contacts 79. The interval between bank contacts 78 and 79 represents a space between two characters. After wiper 43 passes over the contact 79 a "dot" indication is trans-

mitted, after which a dead contact again indicates a space in the code. Contacts 80 again transmit the equivalent of a "dot" after which another interval occurs before an additional "dot" is transmitted from contacts 81. The dispatcher thru the medium of his receiver "RC" hears the indication transmitted from the wiper 43 as comprising a "dash" and three "dots" which in the Morse code is an indication of the letter "B". The dispatcher therefore has heard the letters "A" and "B" transmitted from the location "K" on the railroad track which indication informs him that a train is passing this particular station.

As wipers 42 and 43 are rotated wipers 40 and 41 are at the same time advanced. After wiper 43 leaves bank contacts 81 wipers 40 and 41 engage the first ones of their set. Wiper 40 continues to rotate but over dead contacts under control of stepping magnet "M" until it engages the first of a set of bank contacts 71, this interval of time between the disengagement of wiper 43 from contacts 81 and the engagement of wiper 40 with the contacts 71 is an interval of time of sufficient duration to indicate to the dispatcher of the ending of the first code and the beginning of the second so that he will not mistake it as part of the letters or signals of the location code. Wiper 40 closes a circuit from battery thru the first one of bank contacts 71 thru armature 14 in its front contact (relay "DS" being locked energized at this time), conductor 64, resistance "R1", thru the winding of the coder relay "CO" to grounded armature 18. The wipers 42 and 43 at this time are rotating in an arc away from their bank contacts and are therefore ineffective to operate the coder relay "CO". The bank contact 41 is likewise ineffective at this time due to relay "DN" not being energized to close its armature 11.

Wiper 40 in rotating over its four bank contacts 71 is effective to transmit the equivalent of a "dash" over the dispatcher's line. Before encountering both the bank contacts 72, wiper 40 engages a dead bank contact to permit a break in the code before the "dot" character is transmitted when wiper 40 engages and leaves bank contacts 72. The code letter "N" which in the Morse code is represented by a "dash" and "dot" is therefore transmitted over the dispatcher's line and he is accordingly informed that the train is proceeding over the railroad track in a northerly direction.

The code switch continues to operate and repeatedly sends the code letter "AB" indicating the location of the station, and the letter "N" indicating the direction of the movement of the train, until stopped by the dispatcher.

Assume now that a train is proceeding along the railroad track in the opposite or southerly direction, it will therefore encounter the track section "J" first and this action deenergizes the track relay "TN", which in turn energizes relay "CN" from its armature 5. At armature 7 relay "CN" closes a circuit by way of armature 12 and its back contact thru the winding of directional relay "DN" to battery. At armature 9 relay "DN" disconnects the operating circuit of relay "DS". At its armature 10 it prepares a locking circuit for itself, while at armature 11 it prepares the circuit through wiper 41 for energizing the coder relay "CO". Relay "SN" is likewise energized over a branch circuit from armature 7 of relay "CN". As before no further action takes place as the train passes thru the insulated section of the track "K" but immediately upon entering the

track section "L" relay "TS" deenergizes which in turn closes the circuit for relay "CS" which at armature 8 closes the circuit for relay "SS". A branch of this circuit extending to armature 9 is ineffective at this time due to the energization of relay "DN". With relays "SS" and "SN" energized the locking circuits for the relays "SN", "SS" and "DN" are again completed as before from grounded armature 25. At armatures 18 and 23 the circuit to the stepping magnet "M" is completed, while at armatures 19 and 24 the repeating coil "IC" is cut in circuit of the conductors 54 and 55 extending to the dispatcher's line 50 and 51. The wipers are rotated as before with wipers 42 and 43 transmitting the code representing the letters "A" and "B" to indicate the way-station. Wiper 41 in this instance however, is rendered effective, while wiper 40 has a circuit thru it rendered incomplete at open armature 14. Wiper 41 upon encountering bank contact 73 transmits a "dot" and the same at bank contacts 74 and 75, each "dot" separated by a short interval as the additional dots are transmitted. The three dots correspond to the letter "S" which indicates a south-bound movement of the train over the track section "J", "K" and "L" of the way-station. The signals continue to be transmitted after the train has passed southwardly thru the section "L". It will be appreciated that if the railroad track ran in an east or west direction the Morse code letters corresponding to these directions would be transmitted to the dispatcher by merely strapping together the bank contacts over which wipers 40 and 41 30 rotate in the proper manner. In a similar manner the bank contacts accessible to wipers 42 and 43 may be strapped together in any suitable manner to transmit "dots" or "dashes" indicating letters corresponding to any particular way-station or point in a track from which it is to determine the movement of the trains.

After a dispatcher has heard the signals caused by the passage of a train a number of times to his satisfaction, he will stop the transmission by transmitting a series of impulses from any well known type of key sender over his dispatcher's line to actuate the usual type of railroad selective switch indicated diagrammatically at "SL". This switch is of well known construction one 50 of which is usually provided at each way-station for the dispatcher to signal an attendant or for performing other functions. A switch of this general type is disclosed in Patent Number 1,200,095 issued to J. C. Field, October 3, 1916. In response to the impulses transmitted from the dispatcher the electromagnet 44 of the selector "SL" is actuated and rotates the wiper 45 into engagement with a bank contact to which the conductor 46 is connected. At this point it 55 may be pointed out that the condenser "C" in the line circuits 54 and 55 including the secondary winding 48 of the induction coil "IC" prevents operation of the selector magnet 44 when the code switch is operated to transmit its code. With wiper 45 in engagement with the bank contact to which conductor 46 is connected, ground is extended from the wiper thru the windings of stop relay "ST" to battery. Upon energization of the stop relay "ST" it closes its armature 26 on its front contact to complete a locking circuit for itself from ground on armature 12. This is to insure the energization of the stop relay "ST" sufficient time to allow complete release of the apparatus in case the dispatcher 70 75 immediately restores selector switch "SL". At

the back contact of armature 26 stop relay "ST" opens the circuit of the stepping magnet "M". This action immediately stops the rotation of the wipers of the code switch. At armature 27 and its back contact a point in the line circuit 54 and 55 thru the induction coil "IC" is opened to prevent further sending. At the back contact of armature 25 the locking circuit for relays "SN" and "SS" extending over armatures 16 and 21, 17 and 22 and their front contacts is opened. The locking circuits of relays "DN" and "DS" depending on which was energized, is likewise opened at armatures 15 and 20, and these relays restore. At armatures 19 and 24 further points in the line circuits 54 and 55 are opened while at armatures 18 and 23 the locking circuit for the stop relay "ST" is opened as well as the circuit of the coder relay "CO". Relay "ST" will remain energized as long as the selector "SL" is in its set position from which it will be subsequently released by action of the dispatcher. The apparatus including all of the relays has now assumed its normal operative position and it remains so as long as no trains are advancing thru the track sections. The wipers 40 to 42 inclusive remain in the position in which they are stopped and should they be subsequently operated by the passage of a train they may transmit a mutilated code in only the first rotation across their bank contacts. This however is not 30 detrimental to the transmission of the code however, because the dispatcher listens in until he has heard several repetitions of the code when he will know exactly what it is.

From the foregoing operations it will be apparent that, as a train encounters the track sections, relays "TN" and "TS" operate in succession depending on the direction of the movement of the train. Relays "CN" and "CS" also are operated and in turn start relays "SN" and "SS". Of the directional relays "DN" and "DS" however, only one will be operated because this one will upon operating prevent the other from energizing. The directional relay which is operated closes a circuit through one of the wipers 40 and 41 to render it effective to transmit its code.

In case it should happen that a train enters the track section "L" and proceeding in a north- 50 erly direction may or may not encounter track section "K", but instead of proceeding into track section "J", it reverses and backs out of the section "L" again. In an instance of this kind it would not be desirable to inform the dispatcher of the action of the train inasmuch as it has not completely passed a way-station or point in the track. The track relay "TS" would therefore only be operated, that is, short circuited to drop back its armature 6 on its grounded back contact to close the circuit to control relay "CS". Relay "CS" upon energizing closes ground on its front contact and armature 8 to energize relay "SS". A branch of this circuit extends over armature 9 and its back contact to energize directional relay "DS". The train after backing out of track section "L" permits track relay "TS" to 60 again energize so that relays "CS", "SS" and "DS" are restored to normal position. From the foregoing it is seen that as only relay "SS" was energized and not relay "SN" a circuit is not completed for operating the stepping magnet "M" 65 and a code is therefore not transmitted to the dispatcher's line. Similarly should a train approach and enter the track section "J" and afterwards back out, relays "TN", "CN", "DN" and "SN", would be operated and released, and 70 75

because relay "SS" is not energized the operating circuit for the code switch is not completed and the code is not transmitted.

It is desirable that the dispatcher should not be advised of the passage along the railroad of hand-cars, work trains or single engines engaged in routing freight cars locally, because he usually does not have a direct supervision of such vehicles. It is for this purpose that at the comparatively short section of track "K" is provided. It will be remembered that in the passage of a regular train the sections "J", "K" and "L" would at some time be over-lapped, so that the operation of relays "SN" and "SS" would overlap. Should a hand-car or short engine pass in a northerly direction thru track section "L", relays "TS", "CS", "DS", and "SS" would operate as before. Upon leaving the track section "L" and entering the insulated track section "K" the aforesaid relays would be restored to normal. The small vehicle thereupon leaves the track section "K" and encounters track section "J" resulting in the operation of relays "TN", "CN", "DN" and "SN" and upon the vehicle leaving the track section "J" the above relays would restore to normal. In each instance pointed out only one or the other of the relays "SN" and "SS" were operated, in neither case were they both operated at the same time. The operation of the code switch is therefore prevented and no signal is transmitted over the dispatcher's line to his position.

It will be understood from the foregoing arrangement that a number of way-stations arranged with equipment similarly to that described may be situated along the lines of the railroad at certain points and each connected to the dispatcher's line as indicated at "W" so that he will be aware at all times of the continuous passage of a train from the way-station to way-station without any action on his part except to release the apparatus at each station after it has been automatically operated by the train.

What is claimed is:

1. In a railway signaling system, a railroad track section, a dispatcher's line, a first and second directional means operated responsive to the passage of a train over said track section, means for determining the direction of train travel dependent upon which one of said directional means is first operated, and means responsive to the operation of the last directional means for transmitting a signal to said dispatcher's line comprising a coded signal indicative of the location of said track section and another signal indicative of the direction of movement of said train.

2. In a railway signaling system, a local station, a dispatcher's line connected to said station, a pair of track sections at said local station, signal transmitting mechanism at said local station connected to said track sections, directional means in said signal mechanism automatically operated upon the passage of a train over one of said track sections to determine the type of signal to be transmitted and means in said signal mechanism automatically operated upon the entrance of the train into the other track section for operating said signal mechanism to transmit a signal to said dispatcher's line characteristic of said local station and an additional signal of a character depending upon which of two sections the train entered first.

3. In a railway signaling system, a local station, a dispatcher's line connected to said sta-

tion, a railroad track divided in two sections at said station, signal transmitting mechanism connected to each of said two sections of track, a first and a second means in said signal mechanism operated responsive to the passage of a train over the first and second sections of track, means responsive to the operation of the last of said means for operating said mechanism to transmit a signal to said dispatcher's line identifying the local station and means responsive to the operation of said mechanism to transmit another signal depending on which track section the train has entered first to indicate the direction in which the train is moving.

4. In a railway signaling system, a local station, a dispatcher's line connected to said station, a railroad track divided into sections at said local station, signal transmitting mechanism at said local station connected to each of said sections, means in said signal mechanism operated responsive to the passage of a train over the first of said track sections to select a code, a second means in said mechanism operated responsive to the passage of the train therefrom into the second of said track sections for operating said mechanism to transmit said selected code signal to said dispatcher's line indicating a direction of movement of said train, said second means of said signal mechanism also operated responsive to the passage of a train first into the second track section to select another code and said first means responsive to the passage of the train therefrom into the first track section for operating said mechanism to transmit a signal to said dispatcher's line indicating a movement of the train in the opposite direction, and additional means in said signal mechanism operated by the passage of a train in either direction of movement to transmit a different code signal to said dispatcher's line identifying the local station at said track sections.

5. In a railway signaling system, a local station, a dispatcher's line connected to said local station, a railroad track divided in to a first and second section separated by a third section, signal transmitting mechanism at said local station connected to said first and second sections of track, means in said signal transmitting mechanism operated responsive to the passage of a train over all of said sections in succession to transmit a directional signal to said dispatcher's line depending upon which of said sections is encountered first by said train, additional means in said signal mechanism also transmitting a station identifying signal in either case, and means for rendering said signal transmitting mechanism inoperable to transmit said signals in case said train encounters only said first section, only said second section, only said first and third sections, or only said second and third sections of railroad tracks.

6. In a railway signaling system, a local station, a dispatcher's line connected to said local station, a railroad track at said local station divided into first and second sections insulated by a third section, signal transmitting mechanism at said local station connected to said first and second sections of track and said dispatcher's line, said signal mechanism operated by the passage of a train over said sections only when said train is on all of said sections of track at one time, and remaining unresponsive in case said train encounters two or less of any of said sections, and means responsive to the operation of said signal transmitting mechanism for trans-

mitting signals to said dispatcher's line indicative of the direction of movement of said train over said track sections and depending upon whether said first or said second sections are 5 encountered first, said signal mechanism also transmitting signals in either case indicative of the local station at said railroad track.

7. In a railway signaling system, a local station, a dispatcher's line connected to said local 10 station, railroad track sections adjacent to said local station, signal transmitting mechanism connected to said track sections and said dispatcher's line, means in said signal transmitting mechanism operated responsive to the passage of a 15 train over said track sections to transmit signals to said dispatcher's line identifying the local station and the direction of movement of said train over said track sections, and means for maintaining said signal transmitting mechanism operating persistently after said train has passed 20 beyond said track sections.

8. In a railway signaling system, a local station, a dispatcher's line connected to said local station, a track section at said local station, signal 25 transmitting mechanism at said local station connected to said track section and to said dispatcher's line, said signal mechanism operated responsive to the passage of a train over said track section to transmit signals to said dispatcher's line 30 indicative of said local station and the direction in which said train is moving, said signal mechanism operating continuously to transmit said signals after said train has passed thru and beyond said track section, and means at the 35 local station controlled by the dispatcher over said dispatcher's line for stopping the operation of said signal mechanism.

9. In a railway signaling system, a local station, a dispatcher's line connected to said local 40 station, a pair of track sections at said local station, signal transmitting mechanism at said local station connected to said track sections and said dispatcher's line, said signal mechanism operated automatically responsive to the passage of a train 45 over one of said track sections to select one of two codes operated only after the train passes into the other of said sections to inductively transmit said selected code signal to said dispatcher's line identifying said local station and 50 the direction in which said train is moving over said track section, said coded signals transmitted over said dispatcher's line without interfering with the normal signaling and telephone functions of said line, and means controlled from said 55 dispatcher's line for stopping the operation of said signal transmitting mechanism at will.

10. In a railway signaling system, a local station, a dispatcher's line connected to said local station, a railroad track at said local station divided into two sections, a signal transmitting switch at said station, a directional relay controlled from each of said track sections, one of said relays operated by the passage of a train over its associated track section to start the operation of said signal transmitting switch and transmit a signal to said dispatcher's line indicating the direction in which said train is proceeding, the operated directional relay at the same time preventing the operation of the other 65 of said relays, and means for locking said operated directional relay in energized condition to continuously operate said signal transmitting switch after said train has passed beyond said track sections.

75 11. In a railway signaling system, a local sta-

tion, a dispatcher's line connected to said local station, a railroad track at said station divided into two sections, a signal transmitting switch at said station connected to said dispatcher's line, a directional relay for each of said track sections, 5 means responsive to the passage of a train over one of said track sections for operating only the associated directional relay, said operated relay operating said signal transmitting switch to transmit a signal to said dispatcher's line indicating that the train has entered the corresponding track section, said signal transmitting switch further operating to transmit a signal identifying the local station, and means controlled by the operator from the dispatcher's line for stopping 10 the transmission of said signals from said switch. 15

12. In a railway signaling system, a local station, a dispatcher's line, two sections of track at said local station, a separate start relay and a directional relay connected to each of said track 20 sections, means responsive to the passage of a train over both track sections for operating both of said start relays but only one of said directional relays depending on which of said track sections was encountered first by said train, a signal transmitting switch connected to said dispatcher's line, said switch operated by both of said start relays to transmit a signal to said dispatcher's line depending upon which directional relay is operated to give an indication of the direction in which the train is proceeding, a stop relay, and means for operating said stop relay to stop the operation of said switch. 25

13. In a railway, signaling system, a local station, a dispatcher's line, two sections of track at 30 said station, a dispatcher's line, a separate start and a directional relay controlled from each of said track sections, means responsive to the passage of a train over both of said track sections for operating and locking energized both 35 of said start relays and only one of said directional relays depending which of said track sections was encountered first by said train, a signal transmitting switch at said local station inductively connected to said dispatcher's line, said 40 switch operated by said start relays to first transmit a coded signal to said dispatcher's line indicating the local station and then to transmit a coded signal indicating the direction of movement 45 of said train depending on which directional relay is operated, and means for opening the locking circuit of said relays and stopping said switch. 50

14. In a railway signaling system, a local station, a series of track sections thereat, a dispatcher's station, a signal transmitter at the local 55 station, a line connecting the two stations, a pair of relays at the local station, said relays operated successively responsive to the passage of a train over the track, said transmitter controlled by the first of said relays to be energized to determine the 60 signal to be transmitted, and responsive only to the energization of the other relay to transmit the signal, thereby transmitting a directional signal only when both relays are energized and the signal determined by the relay which is first energized. 65

15. In a railway signaling system, a railroad track section, a dispatcher's line, a transmitting device at said section, code transmitting means in said device, a first code connection normally 70 connected to said transmitting means, said first connection corresponding to said track section, a normally disconnected second code connection corresponding to one direction of train travel over said section, a normally disconnected third 75

code connection corresponding to the opposite direction of train travel over said section, means responsive to a train entering said section for connecting either said second code connection or said third code connection to said transmitting means dependent upon the direction of train travel, and means also responsive to the train

entering said section for operating said device and transmitting means in accordance with said connections to transmit a coded signal indicative of both said track section and direction of travel by said train.

JOHN S. MILLER.
